(57) **CLAIM**

The ornamental design for a pedestal, as shown and described.

DESCRIPTION

FIG. 1 is a perspective view of a first embodiment of a pedestal showing our new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1;

FIG. 7 is a bottom view of the design shown in FIG. 1;

FIG. 8 is a front right perspective view of a second embodiment of a pedestal showing our new design;

FIG. 9 is a front view of the design shown in FIG. 8;

FIG. 10 is a rear view of the design shown in FIG. 8;

FIG. 11 is a right side view of the design shown in FIG. 8;

FIG. 12 is a left side view of the design shown in FIG. 8;

FIG. 13 is a top view of the design shown in FIG. 8; and,

FIG. 14 is a bottom view of the design shown in FIG. 8.

The broken lines shown in the figures are included for the purpose of illustrating portions of the pedestal and form no part of the claimed design.

1 Claim, 14 Drawing Sheets
